UNITED STATES PATENT OFFICE.

RICHARD F. GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,335,327.

Specification of Letters Patent. Patented Mar. 30, 1920.

Application filed August 21, 1916. Serial No. 115,939.

To all whom it may concern:

Be it known that I, RICHARD F. GILE, a citizen of the United States, and a resident of Cliftondale, in the county of Essex and 5 State of Massachusetts, have invented a new and useful Improvement in Internal-Combustion Engines, of which the following is a specification.

My invention relates to internal combustion engines and more especially to engines 10 of the combined pump and motor cylinder type, either single or double acting, and its object is to provide a simple and efficient means actuated by an auxiliary crank shaft 15 for controlling the motion of the sub-piston.

The drawings which accompany and form 20 a part of this specification show an illustrative embodiment of my invention, but it is to be understood that the construction 25 herein particularly described may be widely varied without departing from the scope of my invention as defined by the appended claims.

In the drawings—

25 Figure 1 is a central longitudinal section of a single acting engine embodying my improved sub-piston control. Fig. 2 is a central longitudinal section taken on the line 2—2 of Fig. 1. Figs. 3, 4, 5 and 6 are diagrams showing the positions of the moving parts at various points in the cycle.

In the particular drawings selected for 30 more fully disclosing my invention, 1 represents a frame, herein shown as a two-part casing having its parts connected by the bolts 2 and inclosing the lower portion of the engine. Secured to the top of the casing by the bolts 3 is a cylinder 4, the lower end of which is open and projects into said casing and the upper end of which is closed 35 by the head 5 attached by the bolts 6 and is provided with a number of fuel passages or flutes 7 arranged lengthwise in its bore and communicating with the combustion chamber A. Any suitable number of flutes, say 40 from 16 to 20, more or less, may be used. A spark-plug 8 is screwed into the cylinder head, its points projecting into the combustion chamber, and the cylinder and head are 45 water-jacketed as shown at 9, 10.

Arranged to reciprocate within the cylinder is a power piston 11, herein shown as a trunk piston, and a double pitman 12 engages the pin 13 secured in the walls thereof 50 and connects said piston to the wrist pin 14

of the crank 15 to transmit the power developed in the cylinder to the main crank shaft 16 journaled in the bearings 17 integral with the engine frame. A sub-piston 18 is arranged to reciprocate within the cylinder between the power piston and the combustion chamber, and its rod 19 passes through and is guided by a longitudinal bore in the central core of the power piston, its lower end being pivotally connected to the link 20 which in turn engages the lever 21 shown in the present instance as a bifurcated elbow-lever pivotally connected to the auxiliary crank shaft 22. The auxiliary crank shaft has bearings in the engine frame located above and to the rear of the bearings 17 of the main crank shaft, and is provided with a crank 23 which as shown may be integral therewith. The connecting rod 24 is in pivotal engagement with the auxiliary 75 crank 23 and the shorter arm 25 of the bell crank 25, 26 which is arranged to oscillate about the stationary shaft 27 secured in the bearings 28, or else is fixed with respect to 80 said shaft which in such case will become a rock-shaft oscillatable in said bearings. The longer arm 26 of the bell crank is pivotally connected with the lever 21 by the link 28 which is attached to said lever by the stud 29 secured between the two sides thereof at the center of the elbowed portion of 85 the same. It is necessary that the main crank 15 and the auxiliary crank 23 should have a fixed relative position the one with respect to the other at all points in the cycle, 90 and this is accomplished in the present instance by gears 30, 31, secured respectively to the main shaft 16 and auxiliary shaft 22 and having the same number of teeth together with the intermeshing gear 32 rotatable about the stud 33 secured to the frame. It will be obvious, however, that many other arrangements may be employed to maintain 95 the two cranks in fixed relative position.

The cylinder has an exhaust passage 34 controlled by an inwardly opening valve 35 normally held to its seat by the spring 36 which surrounds the valve stem 37 and bears against the valve housing and the collar 38 on said stem. The valve may be opened by 100 any suitable mechanism such for example as the tappet 39 actuated by the cam 40 which cooperates with the head 41 thereof, gearing (not shown) being employed to 105 connect the cam shaft 42 with the crank 110

shaft or with the auxiliary shaft 22. It will be understood, however, that the particular means disclosed for operating the valve constitutes no part of my invention and that the valve controlling mechanism may be operated directly by the shaft 22 or any other moving member.

The fuel inlet 43 is so located that it is always closed by one of the two pistons except during the admission of a fuel charge, so that no valve need be provided for said inlet. The location of the fuel inlet as shown in Fig. 4 is such that the lower face of the sub-piston when the latter is at the end of its down-stroke is about in line with the lowermost portion of the inlet.

It will be understood of course that the foregoing detailed description comprises various elements which in the precise form shown in the drawings and described herein are not essential to my invention and that these parts may be considered simply as typical of the necessary elements of an internal combustion engine.

25 By means of the flutes or fuel passages 7 I secure an intimate and substantially perfect mixture of the fuel charge and this results in practically complete combustion. As the power piston approaches the head of the sub-piston the charge which is contained in the space between these two elements is compressed and forced by such compression around the advancing head of the sub-piston through the restricted passage afforded by 30 the flutes or fuel passages and is shot with great force against the cylinder head in a member of relatively small streams.

An explosion of the compressed charge in the combustion chamber acts directly on 40 the head of the sub-piston and by the latter is communicated to the power piston. It is absolutely necessary that the two pistons shall travel at the same rate of speed without the slightest relative movement until the sub- 45 piston shall have covered the inner ends of the flutes. The reason for this will be obvious from an inspection of Fig. 1 in which the parts are shown in the position occupied immediately prior to ignition in the combustion chamber A. Should the power piston begin to move away from the sub-piston before the latter covers the inner ends of 50 the flutes, a portion of the effect of the explosion will be exerted against the lower 55 face of said sub-piston in opposition to the force exerted on the upper face thereof. It is essential also that the subsequent relative movement between the pistons be created positively.

60 The positive movement of the sub-piston with respect to the power piston is created by the crank 23 which communicates the necessary motion to the sub-piston through the connecting rod 24, the bell crank 25, 65 26, the connecting rod 28, the lever 21 and

the link 20. The operation of these elements will be explained with reference to Figs. 3, 4, 5 and 6 on which the several moving parts are indicated by lines identified by reference numerals corresponding to those used on Figs. 1 and 2 and provided with exponents I, II, III, etc., to designate the successive positions of the parts.

When both pistons are at the upper ends of their strokes (explosion position) 75 as shown in Figs. 1, 2 and 3, and the charge compressed in the combustion chamber, the valve 35 being closed, the charge is fired and the resulting explosion causes both pistons to descend at the same initial 80 rate of speed and without any relative movement substantially until the power crank which rotates in the direction of the arrow has passed from its initial position 15 (Fig. 3) to position 15' (Fig. 4) approximately 150 degrees therefrom, at which point the crank 23 and connecting rod 24 are in alinement and the longer arm 26 of the bell crank and the lever 21 connected thereto are at their lowermost positions.

90 The pressure created by the explosion therefore follows and acts upon the pistons and by them is transmitted to the main crank during almost five-twelfths of a revolution, so that by far the greater part of the 95 energy of the charge is utilized and the gas is exhausted at a very low pressure, the engine card having, in fact, many of the characteristics of a steam-engine card.

The sub-piston has now reached the lower 100 end of its stroke at 18' and remains momentarily stationary covering the fuel inlet 43. The sub-piston just before reaching the end of its stroke begins to lag and the power piston moves away therefrom. The power 105 piston continues its descent until it reaches the end of its down-stroke (position 11'', Fig. 5) the crank now being at 15'', but immediately after the crank arrived at 15' and while the power piston was descending from 110 11' to 11'', the sub-piston began to ascend, the rock shaft 27 being rotated clockwise by the movement of the crank 23 beyond 150 degrees and thereby forcing the connecting rod 28 upwardly, so that in the position of 115 the parts represented in Fig. 5 the power piston is momentarily stationary and the sub-piston moving upwardly. The connecting rod 24, the bell crank 25, 26, the connecting rod 28, and the lever 21 constitute a 120 motion-multiplying device whereby the upward movement of the sub-piston is made extremely rapid as compared with the upward travel of the power piston, said sub-piston reaching the end of its up-stroke 125 when the main crank is at about 225 degrees from initial position, or 45 degrees beyond its position 15'' (Fig. 5) and the arm 26 of the bell crank and the connecting rod 28 are in alinement. The relative movement 130

between the pistons creates a vacuum or a partial vacuum in the space between the same and a charge of fuel is drawn into said space, and, as will be evident, the pumping 5 action which sucks in the charge is caused mainly by the rapid upward movement of the sub-piston, for the power piston travels but a short distance from the position it occupies at the end of the down-stroke of the 10 sub-piston to its position 11" which is the end of its own down-stroke. The exhaust valve 35 opens slightly before the sub-piston reaches the end of its down-stroke, and the burnt gases of the preceding explosion 15 are mechanically expelled by the up-stroke of the sub-piston.

The crank 15 continuing its counter-clockwise rotation, the power piston ascends and as soon as it has covered the fuel inlet, it begins 20 to compress the charge in the space between its upper face and the lower face of the sub-piston. By virtue of its rapid upward movement, the sub-piston has almost reached the end of its up-stroke before the 25 power piston covers the fuel inlet. While the main crank is moving from a point about 225 degrees from initial position back to said position (shown at 15^{vi} Fig. 6) the sub-piston remains practically stationary. From this point until the main crank reaches its initial position the sub-piston settles back a fraction of an inch (18^{iv}), then advances to 18^v which corresponds to 30 position 18^{vi} and finally arrives at explosion position 18^{vii} which corresponds to position 18, the successive positions of the lower face of the sub-piston and those of the elements 15, 23, 26 and 21 being shown in dotted lines in Fig. 6.

40 A portion of the gas compressed in the space between the pistons passes around the head of the sub-piston by way of the flutes to the combustion chamber and pneumatically expels the remaining portion of the burnt gas through the exhaust passage 45 whereupon the exhaust valve closes preferably shortly after the power piston has covered the fuel inlet and before any loss of the new charge through the exhaust. The 50 charge compressed by the power piston is driven with great force through the flutes into the combustion chamber thereby shooting the charge against the cylinder head in a plurality of relatively small streams and 55 effecting the thorough mixture of the same, until the crank having arrived at its initial position 15, ignition occurs and the cycle is repeated, there being one explosion at the end of every up-stroke or one per revolution 60 of the crank shaft.

It will be obvious that by duplicating the 65 sub-piston control apparatus, my invention may be applied to a double-acting engine having two sub-pistons, one on each side of

While I have described in detail the relative movement of the parts which I have found to be satisfactory in practice, it will be understood that I do not limit myself specifically thereto, for said parts may be 70 variously adjusted and timed and other cycles may be effected.

I claim:

1. An internal combustion engine, comprising a cylinder, a power piston and a 75 sub-piston both arranged to reciprocate within said cylinder, said sub-piston being located between the combustion chamber and said power piston, a main shaft provided with a crank, an auxiliary shaft provided 80 with a crank, means actuated by the last mentioned crank for controlling said sub-piston, and a pitman connecting said power piston to the first mentioned crank.

2. An internal combustion engine, comprising a cylinder, provided with a combustion chamber at one end only, a sub-piston and a power piston both arranged to reciprocate within said cylinder, said sub-piston having a single head located between said 90 combustion chamber and said power piston, a main shaft having a crank, an auxiliary shaft provided with a crank, means actuated by the crank of said auxiliary shaft for controlling said sub-piston, and a pitman connecting 95 said power piston to the first mentioned crank.

3. An internal combustion engine, comprising a cylinder, a power piston and a sub-piston both arranged to reciprocate 100 within said cylinder, a main shaft having a crank, a pitman connecting said power piston to said crank, an auxiliary shaft provided with a crank, and means actuated by the crank of said auxiliary shaft for causing 105 positive movement of both pistons at the same initial rate of speed without relative movement and for causing, subsequently, positive relative movement between the same.

4. An internal combustion engine, comprising a cylinder, a power piston and a sub-piston both arranged to reciprocate within said cylinder, a main shaft having a crank, a pitman connecting said power 115 piston to said crank, an auxiliary shaft provided with a crank, and means actuated by the crank of said auxiliary shaft for causing positive movement of said pistons initially at the same rate of speed without 120 relative movement and subsequently at different rates of speed.

5. An internal combustion engine, comprising a cylinder, a power piston and a sub-piston both arranged to reciprocate 125 within said cylinder, a main shaft provided with a crank, a pitman connecting said power piston to said crank, an auxiliary shaft provided with a crank, and means actuated by the crank of said auxiliary shaft 130

for causing said pistons to travel at the same rate of speed without relative movement until the sub-piston reaches substantially the end of its stroke and for causing, subsequently, positive relative movement between the same.

6. An internal combustion engine, comprising a cylinder, a power piston and an imperforate sub-piston both arranged to reciprocate within said cylinder, a main shaft provided with a crank, a pitman connecting said power piston to said crank, an auxiliary shaft, and means actuated by said auxiliary shaft for causing said pistons to travel at the same rate of speed without relative movement until said crank shall have rotated approximately one hundred and fifty degrees from its initial position, and for causing, subsequently, positive relative movement between said pistons.

7. An internal combustion engine, comprising a cylinder, a power piston and a sub-piston both arranged to reciprocate within said cylinder, a main shaft having a crank, a pitman connecting said power piston to said crank, an auxiliary shaft, means actuated by said auxiliary shaft for causing said pistons to travel at the same rate of speed without relative movement until the sub-piston reaches substantially the end of its down-stroke, for causing, subsequently, positive relative movement between said pistons and for holding the sub-piston substantially stationary at the end of its up-stroke until the power piston shall have completed its up-stroke.

8. An internal combustion engine, comprising a cylinder, a power piston and a sub-piston both arranged to reciprocate within said cylinder, a main crank shaft, a pitman connecting said power piston to said crank, an auxiliary shaft provided with a crank journaled in proximity to said crank shaft, a bell crank journaled in proximity to said crank shaft, a connecting rod pivotally engaging said crank and one of the arms of said bell crank, a pivoted lever, a link connecting the other arm of said bell crank with said lever, and a link connecting said lever to the rod of said sub-piston.

9. An internal combustion engine, comprising a cylinder, a power piston and a sub-piston both arranged to reciprocate within said cylinder, a main crank shaft, a pitman connecting said power piston to said crank, an auxiliary shaft provided with a crank journaled above said crank shaft, a bell crank journaled above said crank shaft, a connecting rod pivotally engaging said crank and one of the arms of said bell crank, a pivoted lever, a link connecting the other arm of said bell crank with said lever, and a link connecting said lever to the rod of said sub-piston.

10. An internal combustion engine, com-

prising a cylinder, a power piston and a sub-piston both arranged to reciprocate within said cylinder, a main crank shaft, a pitman connecting said power piston to said crank, an auxiliary shaft provided with a crank journaled in proximity to said crank shaft, a bell crank having arms of unequal length journaled in proximity to said crank shaft, a connecting rod pivotally engaging said crank and the shorter arm of said bell crank, a pivoted lever, a link connecting the longer arm of said bell crank with said lever at a point intermediate the ends thereof, and a link connecting the outer end of said lever to the rod of said sub-piston.

11. An internal combustion engine comprising a cylinder provided with a combustion chamber at one end only, a sub-piston and a power piston both arranged to reciprocate within said cylinder, said sub-piston having a single head located between said combustion chamber and said power piston, a main shaft having a crank, a pitman connecting said power piston to said crank, an auxiliary shaft having a crank, means for causing the sub-piston to travel in contact with the power piston during a substantial portion of the power stroke and for causing, subsequently, positive relative movement between said pistons, and a member connecting said means to the crank of said auxiliary shaft.

12. An internal combustion engine, comprising a cylinder, a power piston and a sub-piston both arranged to reciprocate within said cylinder, a main shaft having a crank, a pitman connecting said power piston to said crank, an auxiliary shaft provided with a crank, means actuated by the crank of said auxiliary shaft for causing positive movement of said pistons at the same initial rate of speed without relative movement and for causing, subsequently, positive relative movement between the same, and means whereby the charge of fuel in said cylinder is transferred under pressure from the space between said pistons through a restricted passage to the combustion chamber.

13. An internal combustion engine, comprising a cylinder, a power piston and a sub-piston both arranged to reciprocate within said cylinder, a main shaft having a crank, a pitman connecting said power piston to said crank, an auxiliary shaft provided with a crank, means actuated by the crank of said auxiliary shaft for causing positive movement of said pistons at the same initial rate of speed without relative movement and for causing, subsequently, positive relative movement between the same, and means whereby the charge of fuel in said cylinder is mixed during compression.

14. An internal combustion engine, com-

prising a cylinder, a power piston and a sub-piston both arranged to reciprocate within said cylinder, a main shaft having a crank, a pitman connecting said power piston to said crank, an auxiliary shaft provided with a crank, means actuated by the crank of said auxiliary shaft for causing positive movement of said pistons at the same initial rate of speed without relative movement and for causing, subsequently, positive relative movement between the same, and means whereby the charge of fuel in said cylinder is transferred under pressure from the space between said pistons to the combustion chamber in a plurality of relatively small streams.

15. An internal combustion engine, comprising a cylinder having a plurality of fuel passages arranged lengthwise in its bore at one end thereof, a power piston and a sub-piston both arranged to reciprocate within said cylinder, a main shaft having a crank, a pitman connecting said power piston to said crank, an auxiliary shaft provided with a crank, and means actuated by the crank of said auxiliary shaft for causing positive movement of said piston at the same initial rate of speed without relative movement and for causing, subsequently, positive relative movement between the same.

16. An internal combustion engine, comprising a cylinder having a plurality of fuel passages arranged in its bore near one end thereof, said fuel passages communicating with the combustion chamber of the engine, a power piston and a sub-piston both arranged to reciprocate within said cylinder, a main shaft having a crank, a pitman connecting said power piston to said crank, an auxiliary shaft provided with a crank, and means actuated by the crank of said auxiliary shaft for causing positive movement of said pistons at the same initial rate of speed without relative movement, and for causing, subsequently, positive relative movement between the same.

17. An internal combustion engine comprising a cylinder provided with a combustion chamber, a sub-piston and a power piston both arranged to reciprocate within said cylinder, said sub-piston being located between said combustion chamber and said power piston, a main shaft having a crank, a pitman connecting said power piston to said crank, an auxiliary shaft having a crank, means for causing the sub-piston to travel in contact with the power piston during a substantial portion of the power stroke and for causing, subsequently, positive relative movement between said pistons, and a member connecting said means to the crank of said auxiliary shaft.

18. An internal combustion engine comprising a cylinder, a sub-piston and a power piston both arranged to reciprocate within said cylinder, a main shaft having a crank, a pitman connecting said power piston to said crank, an auxiliary shaft having a crank, means for causing the sub-piston to travel in contact with the power piston during a substantial portion of the power stroke and for causing, subsequently, positive relative movement between said pistons and a member connecting said means to the crank of said auxiliary shaft.

19. An internal combustion engine, comprising a cylinder, a power piston and a sub-piston both arranged to reciprocate within said cylinder, said sub-piston being located between the combustion chamber and said power piston, a main shaft provided with a crank, an auxiliary shaft provided with a crank, means for controlling said sub-piston positively throughout the entire cycle, a member connecting said means to the crank of said auxiliary shaft, and a pitman connecting said power piston to the first mentioned crank.

In testimony whereof, I have hereunto subscribed my name this 15th day of August, 1916.

RICHARD F. GILE.
